HYDRAULIC PUMP AND CIRCUIT

John P. Golden, Columbus, Ga., assignor to
 Goldens' Foundry & Machine Company, Co-
 lumbus, Ga., a corporation of Georgia

Application April 18, 1949, Serial No. 88,122

12 Claims. (Cl. 60—97)

1

This invention is concerned with a hydraulic pump and circuit of the type in which a liquid under pressure is supplied to a varying load, such as one or more rams, for actuating the same, illustratively as employed in a cotton baling or like baling press.

One of the features of the invention is the provision of a hydraulic pump and circuit, in which the pump is provided with chambers which operate concurrently in the circuit during the initial operations of the load during which a relatively large quantity of liquid is being delivered at a relatively low pressure; together with an unloading apparatus automatically responsive to the pressure being delivered, whereby one of the pumping chambers is operationally disconnected from the circuit and permitted to idle when a pre-set maximum of this low pressure condition is exceeded.

Another feature of the invention is the provision of a hydraulic pump having multiple chambers of different capacities, the fluid from these pumping chambers being delivered through separate outlet valves into a manifold system, together with a pilot valve responsive to the pressure in the manifold system and effective to control the operation of an unloader valve, whereby to procure movement of this unloader valve when a maximum pressure exists during a low pressure stage of operation of the hydraulic circuit, whereby to disconnect the discharge from one said forcing chamber and pass the effluent thereof to a reservoir and therewith unload the said forcing chamber.

A further feature of the invention is the provision of a pump and circuit system, including an unloader valve for determining the operation of the pump in response to the pressure in a manifold, together with a pilot valve construction which does not respond to the normal pulsations in said manifold while the system is working under a low pressure condition and which responds when the pressure in said manifold attains a predetermined low pressure maximum and thereby procures operation of said unloader valve.

A further feature of the invention is a hydraulic pump and circuit system in which the pump can operate under two different conditions of delivery, at large volumes with low pressure, or at small volume with high pressure; an unloader valve for determining the operation of said pump; a plurality of rams; a ram control valve biased to prevent operation of at least one said ram while the system is at low pressure; and

2

pilot valves responsive to the existing pressure in the system, with one of the pilot valves effective when a predetermined pressure is reached to procure operation of said ram control valve whereby to bring all of said rams into operation and to cause the said pump to continue to operate under the condition of high volume until a high reaction pressure again is present; the other pilot valve being effective when such high pressure is present to procure operation of said unloader valve whereby the pump is caused to operate at low volume and to supply all said rams for obtaining a predetermined high pressure in the individual rams and therewith a high pressure effect upon the load being served by the rams.

With these and other features of construction as objects in view, as will appear in the course of the following specification and claims, an illustrative form of practicing the invention is shown on the accompanying drawings in which:

Figure 1 is a conventionalized diagrammatic layout of one form of construction, indicating the elements and conduit connections.

Figure 2 is an axial upright section through a pump cylinder, with the pump valve.

Figure 3 is an upright axial section through an unloader valve.

Figure 4 is an axial section through a pilot valve, illustratively that for supervising the ram control valve.

Figure 5 is a side view of the sliding member of the pilot valve of Figure 4.

Figure 6 is an upright section through a ram control valve.

In the conventionalized diagram of Figure 1, the pump structure is shown as having a bed 10 upon which are mounted bearings for the crank shaft 11 which is driven from any suitable source of power (not shown) and having a crank pin 12 for the crank rod 13 which is pivoted to the sliding cross-head 14 mounted in the guides 15 on the bed. As shown in Figures 1 and 2, the piston rod 16 extends from the cross head 14 through the packing gland 17 into the cylinder body 18 fixed to the bed 10. The cavity 19 in the cylinder body 18 (Fig. 2) forms a first and larger pumping or forcing chamber having an inlet valve 20 connecting this chamber to the inlet manifold 21, and the outlet valve 22 for connecting the same to the outlet conduit 23. Within the chamber 19, the piston rod 16 has one part 24 of large diameter, and a second part 25 of smaller diameter, this smaller part passing through a further gland 26 and into a second pumping or forcing

chamber 27 which is shown as formed in a separate body piece 28 secured to the cylinder body 18. The second chamber 27 has a valve 29 through which liquid is admitted into the chamber 27, and this second chamber 27 is also provided with an outlet valve 30 for controlling the efflux from this chamber directly to a conduit 31, which is a part of the delivery manifold 32.

A main reservoir or sump 40 is provided at a sufficiently low level to receive drainage from the pump unloader valve and from parts of manifold 32 and other parts: and serves as a discharge point to which the liquid is delivered. It is illustrated as being located above the level of the rams R-1, R-2, and R-3; and connected by gravity supply pipes 120, 122 and the valve RV when correspondingly open, to the rams R-1, R-3. It is customary, in many instances, to use so-called "hydraulic oil" as the liquid in the hydraulic circuit, for the reason that such oil is essentially non-compressible under the operating conditions: and accordingly the liquid will be hereinafter designated as oil. Oil is drawn from the sump 40, for example, through a filter 41, by conduit 42 having a branch 43 connected to the inlet manifold 21, and a branch 44 connected to the inlet manifold 45 for the valve 29. It will be understood that the pump may have one or more sets of cylinders 19, 27, these being served from the manifolds 21, 45 and the illustrated form and delivering to the conduits 23, 31.

While the larger pump chamber 19 for each of the cylinder sets is being employed for delivering oil to the rams, this oil is being forced out through the conduit 23 to the upper end of the control or unloader valve UV and then passes, as will be described in detail hereinafter, through a pipe 50 and a check valve 51 to the manifold 32. When this larger chamber 19 is unloaded, that is, when its action of supply is not desired, its effluent passes through conduit 23 to the upper end of the unloader valve UV, and then by pipe 52 back to the sump 40, thus unloading this larger chamber 19 and the source of power for the pump.

As shown in detail in Figure 3, the unloader valve UV has a body 55, with end plates 56, 57 secured thereto. The upper part 58 of the bore in the body 55 has a smaller section than the lower part 59. The sliding valve has a cylindrical part 60 closely fitting the part 59 and sealed by the packing and shock ring 61 which is pressed into the upper end of the larger bore 59. This sliding valve body also has a larger lower end flange 62 which closely fits the larger bore 59 and acts as a hydraulic piston or actuator. The upper part of this sliding body is hollow and has a cylindrical portion 63 which closely fits the bore 58 and can either shut off passage of fluid from the bore 58 into the conduit 52, in the position shown in Figure 3 or, when the valve body 63 is in raised position, can cut off the flow of fluid into the conduit 50, while opening for flow to the conduit 52. Between the cylindrical portions 60, 63 of the sliding valve body, parts are cut away as at 64 to permit the flow into the conduit 52. The spring 65 presses the sliding valve body toward a normal lower position. A control pipe 70 leads to the lower valve head 57 with an opening therethrough so that oil pressure can be applied against the lower face of the flange 62, the head 57 being hollowed out so that the pressure thus applied is exerted over the entire end face of the sliding valve body. A dis-

charge or release conduit 71 is connected to a port opening into the larger part of the bore 59 at a point normally above the flange 62, but lying opposite this flange and thus cut off when the valve body has been raised to its maximum upward position. The release conduit 71 leads to the sump 40.

The manifold 32, during pumping, is at the prevailing pump pressure during the delivery stroke: that is, it varies from a lower to a higher pressure, and back, as the single cylinder set or the multiple cylinder sets operate, in well known manner. This manifold 32 is connected directly to a central ram R-2, and indirectly to the side rams R-1 and R-3 through a ram control valve RV. In the illustrated form, two pilot valves PV-1 and PV-2 are likewise connected to the manifold 32 and are responsive to the pressure therein and serve respectively to control the ram control valve RV and the unloader valve UV.

A pilot valve construction is shown in detail in Figures 4 and 5. Two pilot valves are illustrated in Fig. 1, and these may be of identical construction. Each has an operation dependent upon the pressure in the manifold 32.

An upper body portion 80 has a circular hollow or cavity 81 with a plane upper end surface 82. A passage or small bore 83 having a cylindrical wall extends the cavity 81 along the axis of the body 80 and is connected to a control branch conduit 84 leading to the manifold 32. A lower valve body member 85 is screwed into the upper body member 80, Figure 4, by its threaded upper projection 86 which has a conically concave recess at its upper end forming a valve seat 87 having a larger effective area than that of the passage 83. This valve seat and the cylindrical hollow or cavity 88 extending downward therefrom are concentric in the valve body members. The upper body member 80 has a port 89 located between the bore 83 and the valve seat 87 and leads to the control conduit 93 for pilot valve PV-1 or conduit 70 for pilot valve PV-2. The lower valve body member 85 has a port 90 below the valve seat 87 and leading to the discharge conduit 71 by its branch 91.

The valve member of the pilot valve is shown in Figure 5 as having a large cylindrical portion 95, a conical seat surface 96 of large effective area at its bottom, a spring engaging stub 97, and a hollow upward extension 98 of small effective area which closely fits and is slidable as a piston in the passage 83 of the upper valve body member 80. The body portion 95 is loose in the cavity 81, leaving an annular space for liquid flow. This extension 98 has a cross bore 99. The valve biasing spring 100 engages the stub 97 and the spring seat 101 which can be adjusted by the screw 102 having the lock nut 103.

The ram control valve RV is shown in detail in Figure 6 as having a body 105 with the upper and lower end plates 106, 107. The valve body 105 has an upper bore 108 of lesser diameter than the lower bore 109. The sliding valve member 65 has a solid cylindrical portion 110 which closely fits the bore 108. A lower flange 111 closely fits the bore 109 and acts as a hydraulic piston or actuator. Extending upwardly from the solid cylindrical portion 110 is a hollow extension portion 112 of the same diameter. Peripheral slots 113 are provided between the portions 110, 112. A spring 114 normally biases the sliding valve body for downward movement. The control conduit 93 communicates with a port 116 in the lower plate 107 so that oil under pressure there-

from can exert a lifting effort over the entire lower end of the sliding valve member. Opening into the bore 109, near the upper end thereof, is a relief or discharge conduit 117 branched from the conduit 71. The manifold 32 connects with a port 118 which is closed off by the upper hollow cylindrical portion 112 of the sliding valve body, when this valve body is in its lower position, whereas this port 118 is opposite the slots 113 when the valve body has been raised. When the valve body is in its lower position, as shown, the part 112 thereof uncovers a port 119 leading to a discharge or relief pipe 120 for returning the oil to the sump 40. The upper end plate 106 of the ram control valve RV communicates with conduits 122 respectively leading to the rams R-1 and R-3.

A branch 125 of the pressure manifold 32 leads to the ram R-2.

A branch 130 from the manifold 32 leads to a quick opening drain valve 131 which may be operated by the lever 132 to permit quick discharge of the contents of the manifold 32, and associated conduits, through the conduit 133, to the sump 40. This valve 131 will also be illustratively assumed to be an over-pressure valve, operating automatically to prevent the pressure in the manifold 32 from rising above 2500 lbs. per square inch in this illustrative form: that is, the valve opens when such pressure is reached, to permit the excess to return to the sump 40.

The operation of this hydraulic pump and circuit, illustratively used in conjunction with a cotton baling press having the press box PB and movable platen MP, can be described as follows:

It will be assumed that the smaller portion 25 of the pump piston displaces one unit of fluid per working stroke, whereas the larger portion 24 of the piston operates in the chamber 19 to displace two units of liquid per stroke. Thus, when the two chambers are working concurrently, three units of fluid are being displaced. It will be assumed that the power for driving the pump shaft 11 is being supplied by a motor which is to operate at a normal load of ten horsepower maximum. The rams R-1, R-2, R-3 are fully retracted. The sump 40 contains oil. The pressure in the manifold 32 will be assumed to start at atmospheric. The sliding member of the unloader valve UV is in its lower position, as shown: and so is the sliding member of the ram control valve RV. The movable member of the pilot valves PV-1 and PV-2 is in raised position. In general, it will be assumed that all conduits are full of oil.

With the baling chamber of the press closed, the pump is started, and now delivers three units of oil per stroke of each of its cylinders. The oil (one unit per stroke) being pumped by the smaller portion 25 of each piston passes directly to the manifold 32. The oil (two units per stroke) being pumped by the larger portion 24 of the piston passes through the conduit 23 to the upper end of the unloader valve UV, thence through conduit 50, check valve 51, to the manifold 32. This manifold is cut off at the drain valve 131, so that pressure is built up therein. The oil in the manifold 32 is stopped by the upper part 112 of the sliding member in the ram control valve, and finds its outlet upwardly in the conduit 125 so that it operates the ram R-2. This is the so-called "central ram" of the cotton press. While the reaction pressure in manifold 32 is gradually rising, its delivery is going to the ram R-2 and therewith the platen or follow-

block of the baling press is being moved against the low resistance of the loosely packed cotton, for example: and this platen MP raises the movable elements of rams R-1 and R-3 while oil flows from the sump 40 through the pipe 120, into the body of ram control valve RV above the sliding member thereof, and thence by pipe 122 to these rams, thus keeping them full of oil.

The resistance of this cotton, during the compression, gradually rises until the pressure reaction from the ram R-2 through conduit 125 causes the fluctuating manifold pressure 32 to rise at maximum to, say, 950 pounds per square inch. As the pressure in manifold 32 rises, its effect has been transferred through the control conduits 84 to the upper end of the small extension 98 of each pilot valve body, but this body has remained within the port 83, although undergoing minor downward movements as the maximum pressure during each pulsation of the pump rises above, say, 900 pounds per square inch as determined by the setting of the valve spring 100. The extension 98 seals the port 83 so that no liquid moves from conduit 84 into chamber 81: and the valve 96 is free of the seat 87 so that the conduit 93 is at essentially the same pressure as conduit 91, i. e. it can drain back to the sump. Assume that this spring has been set in pilot valve PV-1 to permit the final maximum pressure in the manifold 32, for this lower pressure condition of operation, to be 950 pounds per square inch: and in pilot valve PV-2 to be 1000 lbs. per square inch. At this pressure the cross passage 99 of the extension 98 is moved below the plane upper surface 82 in the pilot valve PV-1 so that oil from the manifold 32 now passes through line 84, through the port 83 and the hollow extension 98 with the cross bore 99 thereof, into the chamber 81 around the valve body, thus acting on the upper surface of this body portion 95 to force the same downward against the spring 100, until the valve surface 96 engages the valve seat 87 and closes the same. This closes off drainage through the port 90 and conduit 91 back to the sump, and pressure can now continue to build up since pressure fluid introduced through 84 now acts on the entire upper surface of 95, instead of only on the cross sectional area at the extension 98. The ratio of these areas is purposely made great, so that the valve 95, 96, when once seated, remains fixedly seated: and the pilot valve thus includes parts which serve to maintain the associated control valve, e. g. valve UV, in its operated position when the pressure in the manifold 32 drops. The oil under pressure in the chamber 81 can also pass through the port 92 to the conduit 93. The fluid, passing relatively slowly through the conduits 84 and 93, due to their smaller cross sections and the small cross section of the annular space between the valve portion 95 and the wall of the chamber 81, now comes beneath the flanged end of the valve body in the ram control valve RV, and raises this body. During the first upward movement of the hollow cylindrical portion 112, the port 119 leading to the sump is shut off. Therewith, the action of rams R-1, R-3 in drawing oil through the conduits 122, the upper end of the ram control valve RV, and the conduit 120 from the sump 40, is stopped: and any continued movement of the rams establishes a relative suction, so to speak, on the upper end of the moving valve body of the ram control valve RV. At the end of its upward movement, this control valve now presents the slots 113 opposite the ports 118, and oil from the

manifold 32 can now flow also to the rams R-1 and R-3. The actual "maximum" pressure during the pumping cycle, in the manifold 32 now drops to about $\frac{1}{3}$ of the previous value, or, say 325 pounds per square inch. The pilot valve PV-1 remains in its lower position despite this pressure drop in manifold 32 because the lower pressure, at this time, acts on the entire upper surface of body 95 with a force still sufficient to overcome spring 100. Therewith, also, the pressure per square inch in the upper bore 103 of the ram control valve, and beneath the lower flange 111 thereof, is identical: but the lower surface of the valve is greater in section than the upper, and this excess area above the flange 111 has free drainage by conduit 117, and hence this valve remains in its raised position.

The pump continues to operate, delivering three units of oil per stroke per cylinder, which acts in the three rams, until the pressure in the manifold 32 again rises to and beyond 950 lbs. per square inch. When this pressure reaches 1000 lbs. per square inch, which illustratively is the pre-set loading of the spring in the pilot valve PV-2, the oil from the manifold 32, passing through conduit 84, to the pilot valve PV-2, is now able to depress the sliding valve body in the pilot valve PV-2 until this valve opens as described for valve PV-1, and procures delivery of oil through the conduit 70 to the unloader valve UV, and raises the sliding valve member therein. As this member raises, its upper portion 63 begins to open the port to the conduit 52, so that the pressure of oil from conduit 23 now has an escape by the conduit 52 back to the sump. Thus, the pressure within the upper part of the body of valve UV drops, and oil no longer flows through the conduit 50, and the check valve 51 closes. The continued upward movement of this sliding valve body now closes the port leading to the conduit 50 and fully opens the conduit leading to the sump discharge 52. Under this condition, the larger diameter of piston 16, operating in chamber 18, and delivering two units of oil per stroke per cylinder, now is freed so that its delivery passes back to the sump, efficiently, without significant back pressure being developed upon the pump and its driving power source.

The pump continues to operate with its piston or pistons of smaller diameter 25, however, and these pistons, with a rate of delivery of one unit per stroke per cylinder, continue to build up pressure in the manifold 32, and therewith in the rams R-1, R-2, R-3 while delivering liquid in smaller quantity at a successively higher pressure.

During the stage of operation while all of the fluid from manifold 32 was passing through the conduit 125 to ram R-2, the pressure was building up by three units per stroke per cylinder to a pressure of 950 pounds per square inch, roughly corresponding to a little less than the maximum ten horsepower demand upon the driving motor. When the ram control valve RV is actuated, the same rate of delivery continues, initially from a pressure condition of about $\frac{1}{3}$ that which was employed at ram R-2 immediately before, and again the pressure builds up to about 1000 pounds per square inch, again representing about the maximum ten horsepower load upon the driving motor. At this time, the unloading valve UV operates, and the pump now begins delivery with its smaller piston diameter only, at a rate of one unit of volume per stroke

per cylinder, and operates to increase or boost the manifold pressure in manifold 32 above the 1000 pounds per square inch at which the unloading begins. This condition continues until the driving motor has again reached its maximum output, and the rams are operating at maximum pressure in excess of 2500 pounds per square inch. (Theoretically, with the stated factors, the top pressure would be 3000 pounds per square inch, but in practice it is customary to employ an over-pressure or relief valve 131 at say 2500 pounds per square inch: such a relief valve is old and well known in such systems.)

The operation has thus produced a maximum compression in the cotton present in the baling press, and this cotton is now tied. In order to release the press, and permit the platen to recede, the operator moves the lever 132, usually after shutting down the motor. The valve 131 now opens completely and discharges from the manifold 32 and thus from the ram R-2 with a quick drop of pressure toward atmospheric. When the pressure falls below 1000 pounds per square inch in the manifold 32, fluid has likewise been flowing backward from the unloading valve UV through the conduit 70, so that this valve UV has been drifting toward its lower position. It will be noted that oil can enter the space in the larger bore 59 from the manifold 91 under this condition, this relief manifold pipe 71 having its lower end below the minimum oil level in the sump or reservoir 40. Also, the ram control valve RV has its sliding member drifting downward with discharge of oil backward through the conduit 93 to the pilot valve PV-1. The rams R-1, R-2 and R-3 have been discharging back to the manifold 32 and thus through conduit 130, 133 to the sump: this flow is temporarily closed off for rams R-1 and R-3, at the ram control valve RV, permitted discharge from the rams R-1 and R-3 through port 119 and conduit 120 occurs. It will be noted that as the sliding member in the ram control valve member RV moves downward, oil can enter the larger bore 109 from the conduit 117.

As the pressure in the manifold 32 continues to drop, ultimately the biasing springs 100 in the pilot valves force the bodies 95 upwardly until the extensions 98 have their cross bores 99 totally within the corresponding ports 83 and thus closed off. At this time, the oil from conduits 70, 93 can pass around the valve bodies to the ports 90 and thus by conduit 91 and relief conduit 71 back to the sump.

Rams R-1, R-2, R-3 go back to their initial position and the operator now moves the lever 132 to close the valve 131. The system has now been restored to initial condition, and is ready for the compression of a new bale.

In the foregoing description of operation, the biasing spring of pilot valve PV-1 was stated to have a lesser effect (e. g. to balance 950 lbs. per square inch in the manifold 32) than the biasing spring of pilot valve PV-2 (e. g. to balance 1000 lbs. per square inch in manifold 32). It will, however, be noted that a similar staging operation can be effected if these spring adjustments are reversed, so that the unloading valve first operates, and then the ram control valve. It is also feasible to have the system operate with the two valves moving simultaneously: but this condition is not preferred because it represents a momentary drop of the pump output to one-third of the initial delivery while simultaneously the effective cross sectional area of the rams is

increased to three times the initial area provided by ram R-2; that is, the necessary ratio condition of the two valve seats in the pilot valve PV does not permit so delicate a control, and the pump is running at relatively low efficiency for the available maximum power, as it starts on this continuation of the cycle of operation.

It is obvious that the illustrative form of construction is not restrictive, and that the same might be made in many forms without departing from the scope of the appended claims.

What is claimed is:

1. A hydraulic system including a pump having multiple pumping chambers with inlet and outlet valves, a main conduit connected for directly receiving the liquid pumped from one of said chambers, a varying load device connected to the main conduit whereby varying back pressures are established in the main conduit, a second conduit and a valve device therein for selectively delivering to the main conduit the liquid pumped from another of said chambers and for discharging said latter liquid without passage to said main conduit, and a pilot device responsive to the pressure in the main conduit and connected to said valve device for procuring operation of the same from said delivering condition to said releasing condition upon the event that the pressure in said main conduit exceeds a pre-set maximum.

2. A hydraulic system as in claim 1, in which the said other pumping chamber has a greater capacity than said one pumping chamber, and in which the pilot device includes means for preventing reverse operation of said valve device until the pressure in the main conduit has been reduced essentially to atmospheric.

3. A hydraulic system including a pump having multiple pumping chambers with inlet and outlet valves, a main conduit for directly receiving the liquid pumped from one of said chambers; a plurality of hydraulically operated load devices, of which one is directly connected to said main conduit, a first control valve for selectively connecting another of said chambers to said main conduit and for releasing the liquid pumped from said other chamber to a discharge point without passage to the main conduit, a second control valve for selectively connecting another of said hydraulically operated load devices to the main conduit and for connecting the said other device to a discharge point, and pilot means responsive to the pressure in said main conduit and connected to said control valves effective to procure movement of said control valves when predetermined pressure conditions are attained in said main conduit.

4. A hydraulic system as in claim 3, in which said pilot means include selective devices for causing the first control valve to move from the position of connecting to said main conduit to the position of connecting to the discharge point when the main conduit pressure rises to a first value and to maintain the same in said latter position upon fall of the pressure in said main conduit, and also include selective devices for causing the said second control valve to move from the position of connecting to the discharge point to the position of connecting to the main conduit when the pressure therein again rises and attains a pre-set maximum.

5. A hydraulic system including a reciprocating pump having larger and smaller pumping chambers with inlet and outlet valves, a main conduit for directly receiving the liquid pumped from

the smaller chamber, an unloader valve and associated conduits for receiving the liquid pumped from the larger chamber and effective in one position of the unloader valve for delivering said liquid to the main conduit and effective in another position thereof for releasing said liquid to a discharge, a varying load device connected to said main conduit effective for determining the back pressure therein, said unloader valve having a hydraulically actuated piston for moving the same, a pilot valve structure having a part responsive to the pressure in the main conduit and a biasing device for preventing operative movement of the pilot valve until a pre-set pressure exists in the main conduit, a branch conduit from the main conduit and including said pilot valve and leading to said unloader valve piston for procuring movement of the same when the pilot valve is operated, said movement shifting the unloader valve from delivering to releasing position, said pilot valve structure including members of different effective areas exposed to the pressure at the valve wherewith the member of smaller area is so exposed when the pilot valve is held biased by said biasing device and the member of larger area is so exposed when the pilot valve is in operated position.

6. A hydraulic system including a reciprocating pump having larger and smaller pumping chambers with inlet and outlet valves, a main conduit for directly receiving the liquid pumped from the smaller chamber, a plurality of hydraulic rams of which one is directly connected to said main conduit, a ram control valve effective in a first position for connecting another of said rams to the main conduit and in a second position for connecting the said other ram to a discharge point, said ram control valve having a hydraulically actuated piston for moving the same, a pilot valve structure having a port responsive to the pressure in the main conduit and a biasing device for preventing operative movement of the pilot valve until a pre-set pressure exists in the main conduit, a branch conduit from the main conduit and including said pilot valve and leading to said ram control valve piston for procuring movement of the same when the pilot valve is operated, said movement shifting the ram control valve from said second position to said first position, said pilot valve structure including members of different effective areas exposed to the pressure at the pilot valve wherewith the member of smaller area is so exposed when the pilot valve is biased by said biasing device and the member of larger area is so exposed when the pilot valve is in operated position.

7. A hydraulic system including a reservoir, a power-driven pump with multiple pumping chambers connected for receiving liquid from the reservoir, a main conduit connected directly to one of said chambers, an unloader valve selectively connecting another of said chambers to the main conduit and to the reservoir, two hydraulic rams of which one is connected directly to the main conduit, a ram control valve for selectively connecting the other ram to the main conduit and to the reservoir, said unloader and ram control valves each having a hydraulic actuator, a first pilot valve structure responsive to the pressure in said main conduit and effective when said pressure attains a first pre-set value to permit a first flow of liquid from the main conduit, a first pilot conduit for conveying said first flow of liquid to the actuator of said unloader valve to cause the said unloader valve to move

from delivering to releasing position, said first pilot valve structure including a device for maintaining the same in said first flow permitting position, a second pilot valve structure responsive to the pressure in said main conduit and effective when said pressure attains a second pre-set value higher than said first value to permit a second flow of liquid from said main conduit, a second pilot conduit for conveying said second flow of liquid to the actuator of the ram control valve to cause the ram control valve to move from the reservoir-connecting position to the conduit-connecting position, said pilot valve structures each including a drain connection to the reservoir effective when the pressure in said main conduit falls below a pre-set minimum to cause the liquid moving consequent to said first and second flows to move to the reservoir.

8. A hydraulic system including a reservoir, a power-driven pump with multiple pumping chambers connected for receiving liquid from the reservoir, a main conduit connected directly to one of said chambers, an unloader valve selectively connecting another of said chambers to the main conduit and to the reservoir, two hydraulic rams of which one is connected directly to the main conduit, a ram control valve for selectively connecting the other ram to the main conduit and to the reservoir, said reservoir being connected and positioned for gravitational flow of liquid therefrom to said other ram, said unloader and ram control valve each having a hydraulic actuator, a first pilot valve structure responsive to the pressure in said main conduit and effective when said pressure attains a first pre-set value to permit a first flow of liquid from the main conduit, a first pilot conduit for conveying said first flow of liquid to the actuator of said unloader valve to cause the said unloader valve to move from delivering to releasing position, said first pilot valve structure including a device for maintaining the same in said first flow permitting position, a second pilot valve structure responsive to the pressure in said main conduit and effective when said pressure attains a second pre-set value higher than said first value to permit a second flow of liquid from said main conduit, a second pilot conduit for conveying said second flow of liquid to the actuator of the ram control valve to cause the ram control valve to move from the position permitting gravitational flow from the reservoir to the position of connecting said other ram to the main conduit, said pilot valve structures each including a drain connection to the reservoir effective when the pressure in said main conduit falls below a pre-set minimum to cause the liquid moving consequent to said first and second flows to move to the reservoir.

9. A hydraulic system comprising a pump and means for driving the same, said pump having larger and smaller pumping structures, a reservoir from which the pumping structures draw liquid, a main conduit in direct communication with the smaller pumping structure, an unloader valve connected with the larger pumping structure and having selectively connectable outlet ports leading respectively to the main conduit and to the reservoir, said unloader valve having an actuating cylinder and piston, a hydraulically operated variable load connected to said main conduit for supply therefrom, a pilot valve connected to said main conduit and having selectively connectable valve ports leading respectively to the said cylinder and to said reservoir;

said pilot valve including valve seats and a movable member having a part of small area and another part of larger area, said parts selectively engaging a first and a second of said valve seats when the valve member is moved whereby in one position of the valve member the part of small area is exposed to the pressure in the main conduit and flow from the main conduit is stopped at a first valve seat and the member permits flow from the said cylinder-connected port past another valve seat to the reservoir-connected port, and whereby in another position of the member the part of larger area is held to the second valve seat by said pressure and there-with the reservoir-connected port is closed and liquid can flow past the said first seat to the cylinder-connected port; a valve for discharging said main conduit to the reservoir whereby to reduce the pressure in said main conduit, and means for moving the member toward said one position when the pressure in said main conduit is below a pre-set minimum.

10. A hydraulic system including a pulsating pump and means for driving the same, a variable load device, a main conduit connecting the pump and the load device, means including a control valve and effective for controlling the rate of movement of the load device, said control valve having an actuating cylinder and piston, and a pilot structure for procuring operation of the control valve; said pilot structure including a valve body having a hollow and also having connected to the hollow a small bore with a port connected to the main conduit, a sliding valve member having a small cylindrical part engageable in the small bore at a first end portion of the member whereby to close the bore and receive a small force for moving the member along said small bore, said member having also a larger part located in said hollow and said body having a valve seat for receiving said larger part in a second end position of the member, said body having a second port opening to said hollow and effective for releasing pressure fluid from the body, said body having a third port opening to said hollow at a point between said bore and said valve seat whereby said larger part and its valve seat control flow between said second and third ports, said third port being in communication with said cylinder and in selective communication with the second port and with said bore in the said first and second end positions of the member, and a spring acting on the sliding member for urging the small part into closing position in said bore.

11. A hydraulic system as in claim 10, in which the small port has an axial hole and a transverse hole leading therefrom to its periphery, said transverse hole being positioned within the bore in said first end position and thereby closed against flow therethrough.

12. A hydraulically responsive valve having a body with a cavity with axially arranged smaller and larger portions and a bore having a terminal connection, a valve member slidably in said cavity and having a small cylindrical extension at one end and a larger seating surface at the other end, said bore closely receiving said small extension whereby said bore and extension act as cylinder and piston in response to pressure at said terminal connection, said body having a valve seat for receiving said seating surface whereby to close off said larger and smaller portions of the cavity from one another, a port opening to the larger portion of the cavity, and a port

opening to the smaller portion of the cavity; a spring urging said valve member to an end position in which said larger and smaller portions communicate and said terminal connection is closed off from said larger portion, and a screw engaging said spring for regulating the effect thereof and thereby determining the pressure effect at said terminal connection at which said piston moves said member.
